UNITED STATES PATENT OFFICE

DAVID E. ROSS, OF LAFAYETTE, INDIANA

DIRIGIBLE FRAME

Application filed March 11, 1929. Serial No. 346,131.

This invention is an improvement in dirigible air ships of the so called "Zeppelin" type. The object of the present invention is to provide a frame for the body of the airship which will resist both longitudinal and torsional strains, will be of minimum weight for volumetric capacity, and will be practically rigid but have sufficient flexibility to "breathe" without injuring any parts thereof; and also will have very few expensive structural "shapes", and be comparatively inexpensive to build.

The invention in short provides a dirigible frame having an internal compression member, external tension members, distending members for holding the tension members in position and resilient members at the ends of the tension members to prevent undue stresses upon any of the before mentioned members, and prevent abnormal stresses upon the smaller tension members.

More specifically the frame comprises a center compression member, preferably hollow, extending axially through the entire length of the frame; distending members surrounding the compression member, longitudinally disposed tension members, and spirally disposed tension members, said tension members being positioned by the distending members and when inclosed imparting the external contour to the dirigible body. Further the compression member and distending members are so constructed that air is conducted from the point of highest air pressure at the nose of the structure through the hollow compression member and distending members to points rearwardly of the maximum diameter of the body, thus relieving the pressure at the front end of the body and the partial vacuum at the rear of the body, thereby reducing the natural forces tending to retard rapid travel of the dirigible through the atmosphere.

The accompanying drawings illustrate a dirigible body frame constructed in accordance with my invention; and an understanding thereof will enable others to adopt and use the invention. In the claims following the description I have summarized the essentials of the invention and the novel features

of construction and novel combinations of parts for which protection is desired.

In said drawings;

Fig. 1 is a side view of the dirigible frame, the outer covering or "skin" being removed. 55

Fig. 2 is a longitudinal section through Fig. 1, many of the tension members being omitted for the sake of clearness.

Fig. 3 is an enlarged detail sectional view of the frame, the central portion thereof being broken away. 60

Fig. 4 is an enlarged transverse section taken on the line 4—4 Fig. 1.

Figs. 5, 6 and 7 are detail views of various forms of resilient end plates. 65

The central compression member 1 may be of any desired contour in cross section, and is made hollow for the purpose of lightness and strength, and also preferably tapered from front to rear as indicated in Fig. 2. 70 This member may be formed of any suitable metal, having great strength and lightness.

Surrounding this compression member are a series of distending members 2 and 2a, which are preferably annular, and are supported upon the compression member 1 and axially centered relatively thereto by spokes 3 and 3a, the outer ends of which spokes are fastened to the distending members. The inner ends of these spokes may be attached to the compression member in any suitable way, preferably by means of hub pieces 4 and 4a as shown in the drawings. 75

A plurality of tension members 6, which are preferably rods or cables, extend longitudinally of the frame and are attached to the peripheries of the various distending members 2 and 2a and at their extremities to the ends of the compression member. The members 6 are preferably arranged longitudinally of the structure, and impart great stiffness thereto. I further provide other tensional members 7 which preferably extend spirally of the frame from one plate 5 to the other. Two sets of members 7 are employed running spirally in opposite directions as indicated in Fig. 1, the intersecting diagonal tension members 7 forming a network enclosing the distending members and forming therewith an outer frame to which an outer 80

90

95

100

covering or skin (not shown) of any suitable material may be secured.

Preferably the tension members 6 and 7 are attached to resilient annular plates 5 secured to the ends of the compression member 1. The plates 5 are resilient in order to prevent any undue strains on said tension members or on the distending members 2, 2a, or on compression member 1. The plates 5 may be made of various forms, as indicated in Figs. 5, 6 and 7. As shown in Fig. 3, the plates 5 are dished and the ends of the cables 6 and 7 are attached to the peripheries thereof, and the inherent resiliency of the plates equalize the strain on the several tension members.

The resiliency of the end plates can be enhanced by providing them with an increased number of concentric undulations as indicated in Fig. 5. In some cases the plates may be made with radial undulations as indicated in Fig. 7. In some cases the larger tension members 6 can be attached direct to the plates 5 as in Figs. 1 and 6; and the smaller spiral tension members 7 could be connected to an auxiliary annular plate 5b seated against the outer side of the plate 5 as indicated in Fig. 6.

In the construction indicated in Fig. 6 the heavier longitudinal tension members 6 are all connected with the same resilient plates 5 while the lighter spiral tension members 7 are all connected to the same resilient plates 5b, and the one set of tension members does not affect the other, as they would do if all are attached to the same spring plates. In some cases the tension members might be provided with individual tensioning springs, if desired. With the same coefficient of expansion naturally the lighter spiral tension members would shrink and expand more than the shorter longitudinal tension members, and the resilient plates or springs will compensate for various strains on the members.

The spring plates or connections between the tension members 6 and 7 and ends of the compression member 1 are not provided for creating flexibility in the structure itself, but for preventing undue strains on the individual tension members momentarily put upon them. The aforesaid variations merely demonstrate feasible methods of allowing the structure sufficient flexibility to permit it to "breathe" without throwing any undue strain on any of the lighter tension members.

When a dirigible is moving at a high rate of speed through the air the forward part of the body pushes the air ahead of it and compresses the air at its forward end, which tends to retard the speed of the dirigible and the reduced outer contour of the body to the rearward of the maximum diameter thereof tends to produce a low pressure area or partial vacuum, which also has a retarding effect upon the speed of the dirigible.

To overcome these retarding forces the dis-

tending members 2a disposed to the rear of the greatest diameter of the structure are hollow and provided with slots 2b or openings in their peripheries, said slots opening diagonally rearwardly. The spokes 3a are also hollow and communicate at their inner ends with the interior of the compression member 1. Air is conducted from the front end of the dirigible through member 1 through spokes 3a to the distending members 2a and allowed to escape rearwardly from such distending members through slots 2b.

The front end of the member 1 can be opened to allow the highly compressed air to pass into the member 1, and thus reduce the pressure at the front, and as nature abhors a vacuum this immediately causes the air to rush to the point of low air pressure or partial vacuum rearwardly of the maximum diameter of the body and escape at the slots 2b. This reduces high air pressure at the front of the body and relieves the retarding effect on the rear portion of the body; any air that is not discharged onto the skin or outer covering of the body can pass on through the member 1 to fill whatever partial vacuum may have been created at the rear of the dirigible due to its speed. The discharge of the air rearwardly at the rear side of each rear distending member 2a reacts on the skin of the dirigible and tends to force the same forward.

It will be seen that my invention provides a dirigible frame of great strength due to well known engineering laws. The compression member 1 may serve not only as a compression member or stem, but also may be of sufficient size to permit operatives or passengers to pass interiorly through the structure; also to relieve high pressure at the front end of the dirigible by passing the air through the compression member which relieves the aforementioned high pressure at the front of the dirigible and the low pressures at the rear thereof. The air compressed at the front will rush to fill the partial vacuum at the rear and pass at high speed through the central compression member without the aid of mechanical blowers or mechanical mediums for forcing circulation.

The construction described,—comprising a built up body having a compression member, distending members and outer tension members,—has great strength and low weight; is conformable to the laws that the strength of a beam is as the cube of its depth; the surface of circles are to each other as the squares of their diameters; and volumetric displacement as the squares of the diameters.

The spiral form of the outer tension member compensates for torsional strain. Thus a dirigible constructed in accordance with my invention will have great strength compared to its weight and great volumetric displace-

ment allowing it to become more rigid as the cube of its volume increases with the square, making the unit costs reduced for transporting large pay loads.

5 I claim:—

1. A dirigible frame comprising a longitudinal axially disposed tubular compression member forming an air duct, a series of spaced distending members surrounding the compression member and tension members extending spirally lengthwise of the frame and connected to the compression member and to the distending members, said tension members spiralling in opposite directions.

15 2. A dirigible having hollow distending members in rear of the maximum diameter of the dirigible provided with rearwardly opening slots for the escape of air, and means for directing air from the front end of the 20 dirigible into said hollow distending members for the purposes specified.

25 3. In a dirigible frame as set forth in claim 1, springy plates connected to the ends of the compression member, to which plates the ends of the tension members are connected.

35 4. A dirigible having a tubular compression member, and hollow distending members in rear of the maximum diameter of the dirigible provided with rearwardly opening 40 slots for the escape of air, and means positioning the distending members including tubular spokes for admitting air from the compression member into said annular distending members.

45 5. A dirigible frame comprising a tubular compression member forming an air duct, a series of spaced annular distending members concentric to and surrounding the compression member, means for discharging air 50 from the duct at the periphery of the dirigible and in rear of the maximum diameter thereof, means fixedly connecting the distending members with the compression member, and spirally disposed tension members yieldably connected to the ends of the compression member and also connected to the distending members, said tension members spiralling in 55 opposite directions.

60 6. A dirigible frame comprising a tubular compression member forming an air duct, a series of spaced annular distending members concentric to and surrounding the compression member, means fixedly positioning the distending members relative to the compression member, a series of longitudinally disposed tension members connected with the compression member and the distending members, and sets of spirally disposed tension members connected to the ends of the compression member and with the distending members, said tension members spiralling in 65 opposite directions.

65 7. In a dirigible as set forth in claim 6 spring plates connected to the ends of the

compression members and to which the ends of the tension members are connected.

8. A dirigible frame comprising a tubular axially disposed compression member forming an air duct, a series of spaced annular distending members concentric to and surrounding the compression member, means fixedly connecting the distending members with the compression member, a series of longitudinally disposed tension members yieldably connected to the ends of the compression member and also connected to the distending members, and sets of spirally disposed tension members yieldably connected to the ends of the compression member and also connected with the distending members, said tension members spiralling in opposite directions.

9. A dirigible frame comprising a tubular axially disposed compression member forming an air duct, a series of spaced annular distending members concentric to and surrounding the spaced compression member, and spokes fixedly connecting the distending members with the compression member, a series of longitudinally disposed tension members connected with the ends of the compression member and with the distending members, and sets of smaller spiralling tension members connected to the ends of the compression member and with the distending members, said sets of smaller members extending spirally in opposite directions.

10. In a dirigible as set forth in claim 9, some of the distending members at the rear of the maximum diameter of the dirigible being hollow and having rearwardly opening slots for the escape of air, and their spokes being tubular to admit air from the compression member to said annular distending members.

11. In a dirigible as set forth in claim 9, spring plates connected to the ends of the compression member and to which the ends of the tension members are connected.

12. A dirigible frame comprising a tubular axially disposed compression member forming an air duct, a series of spaced annular distending members concentric to and surrounding the spaced compression member, and spokes fixedly connecting the distending members with the compression member, a series of longitudinally disposed tension members yieldably connected with the ends of the compression member also connected with the distending members; and smaller tension members yieldably connected to the ends of the compression member and also connected with the distending members, said smaller members extending spirally in opposite directions.

13. In a dirigible as set forth in claim 12, some of the distending members at the rear of the maximum diameter of the dirigible being hollow and having rearwardly opening

slots for the escape of air, and their spokes being tubular to admit air from the compression member into said hollow distending members.

14. A dirigible frame comprising a tubular axially disposed compression member forming an air duct, a series of spaced distending members surrounding the compression member, spokes connecting the distending members to the compression member, a series of longitudinally disposed tension members yieldingly connected at their ends to the ends of the compression member and also connected at intermediate points to the distending members, and sets of tension members similarly yieldingly connected to the compression member and to the distending members said tension members spiralling in opposite directions.
15. A dirigible frame comprising an axially disposed compression member, a series of spaced distending members surrounding the compression member; tension members extending from one end of the frame to the other and connected at intermediate points to the distending member, said tension members spiralling in opposite directions; and resilient connections between the ends of the tension members and the ends of the compression member to prevent excessive lateral deflecting stresses on the frame breaking said tension members.

16. A dirigible frame comprising a compression member; a series of spaced distending members surrounding the compression member; a series of longitudinally disposed tension members extending from one end of the frame to the other and connected at intermediate points to the distending members; sets of tension members extending spirally lengthwise of the frame, said spiral sets of tension members spiralling in opposite directions; and resilient connections between the ends of the tension members and the ends of the compression member to prevent excessive lateral deflecting stresses on the frame breaking said tension members.

17. A dirigible frame comprising an axially disposed compression member; a series of spaced annular distending members concentric to and surrounding the compression member; tension members connected to the distending members; and spring plates connected to the ends of the compression member to which plates the ends of the tension members are connected to prevent excess lateral deflecting stresses on the frame breaking said tension members.

18. A dirigible frame comprising an axially disposed compression member; a series of spaced distending members surrounding the compression chamber; tension members extending from one end of the frame to the other and connected at intermediate points to the distending members, said tension

members spiralling in opposite directions; and spring plates connected to the ends of the compression member to which plates the ends of the tension members are connected to prevent excessive lateral deflecting stresses on the frame breaking said tension members.

19. A dirigible frame comprising a compression member, a series of spaced distending members surrounding the compression member, a series of longitudinally disposed tension members connected to the compression member and the distending members, sets of oppositely spiralling tension members extending lengthwise of the frame and connected to the compression member and to the distending members, and spring plates connected to the ends of the compression member to which the ends of the tension members are connected.
